UNITED STATES PATENT OFFICE.

JOSEF MERSING, OF ZURICH, SWITZERLAND.

LAMP SHADE FOR USE WITH INCANDESCENT ELECTRIC LAMPS.

Application filed December 12, 1923. Serial No. 680,181.

To all whom it may concern:

Be it known that I, JOSEF MERSING, a citizen of the Swiss Republic, residing at Zurich, Switzerland, have invented certain improvements in Lamp Shades for Use with Incandescent Electric Lamps, of which the following is a specification.

This invention relates to a shade for electric incandescent lamps of the kind composed of two hingedly connected vitreous globe parts and provided with means for transmitting only diffused and reflected light, and its object is to effect certain improvements in the construction of the shade with a view to allow free expansion of the vitreous elements and prevent them from breaking under the influence of the heat.

With this object in view I connect the two parts of the shade to their metal mounts by means of resilient tongues stamped out of the metal, and I connect the shade to its hood carrier by means of a slotted ring which is adjustable on radial screws for clamping the shade to the hood.

Fig. 1 of the accompanying drawings represents a view of the globe according to one construction, partly in section and partly in elevation.

Figs. 2 and 3 are sectional views on a larger scale showing the mode of connecting the globe elements, and

Fig. 4 is a cross-section of Fig. 3.

Fig. 5 is a view of a modified detail.

Fig. 6 is a view of the lamp support,

Fig. 7, a sectional view of part of the support seen at right angles to Fig. 6.

Fig. 8, a cross-sectional detail view of the part shown in Fig. 7, and

Fig. 9, a plan of the lamp support.

Fig. 10 is a view of an arrangement for indirect illumination, and

Fig. 11, a view showing the device combined with an illuminated sign.

The lamp globe is preferably composed of two parts which are connected so that they can be opened out for the admission of the lamp. In the construction according to Figs. 1 to 4, the globe has an upper, bell-shaped part 2 which is either opaque or translucent and which is formed with a conical portion 2^a whose surfaces are set at about 45° with the perpendicular. The incandescent lamp 5, which is of the half-watt type, is arranged with its filament 5^a in the median plane A—B of the conical surface

2^a. Thus the horizontal light rays emitted by the lamp 5 will be reflected by this surface in a substantially vertical direction, either entirely or partly depending on whether the surface is opaque or translucent. If total reflection is desired, the surface 2^a is preferably silvered.

The lower part of the globe closes the mouth of the bell 2. It has a central translucent portion 3 which is substantially concentric with the filament 5^a and which diffuses the light emitted direct by the latter. The portion 3 is surrounded by a transparent ring 3^a through which the reflected rays from the surface 2^a are projected towards the surface to be illuminated. Thus, maximum lighting effect will be obtained while the lamp filament is shaded so as not to be directly in view.

The manner of connecting the two parts of the globe is illustrated in Fig. 2. The bell 2 is fitted with a metal rim 4 which is suspended on a beaded flange 9 and connected to the latter by means of resilient tongues 12 which are bent round the bead after the elements have been assembled. The lower part of the globe is mounted in a ring 6 which is hinged at 7 to the rim 4 and which is connected to the globe part by means of resilient tongues 11 applied to the bead 10. One or more screw clamps 8, which are connected to the rim 4, are used for holding the ring 6 in closed position. The parts can easily be turned open about the hinge 7 when the lamp 5 requires attention or renewal. The tongues 11 and 12 are cut out of metal strips which are riveted or soldered to their support. As these tongues can yield easily to the expansion of the vitreous elements 2 and 3, a breakage of the latter by the changes in the temperature is effectively obviated. The rim 4 is provided with ventilating apertures 13 which may be covered with gauze in order to exclude dust and insects.

The globe is fitted in a holder composed of a hood 1 which is also provided with gauze-covered air vents 27 so that the air can circulate freely and reduce the temperature of the lamp. The connection of the globe to the holder is also effected with a view to allow the vitreous elements to expand uniformly. The hood 1 has two cylindrical, stepped portions 15 and 16 and terminates in a conical rim 17. Inside the

hood a ring 14 is arranged which is also formed with two cylindrical stepped portions 20 and 21 and a conical rim 23. The hood 1 is fitted with radially adjustable screws 19 which are held in bosses 18 connected to the portion 15. The corresponding portion 20 of the ring 14 is formed with slots 25 for engagement with the screws 19. The slots are preferably tapered so as to 10 present a wide inlet to the screws. At all events the upper edges of the slots are inclined so that a rotary adjustment of the ring, which rests by means of said edges on the screws, is accompanied by an axial displacement of the ring relative to the hood. There is a flange 22 at the upper edge of the ring, and this flange is formed with notches 26 above the highest parts of the slots 25. The bell 2 is clamped between the rims 17 20 and 23. In assembling the elements, the bell 2 is suspended on the rim 23 while the ring 14 is inserted into the hood. To allow the flange 22 to pass the bosses 18, the hood must be turned until the bosses 18 register 25 with the notches 26. When the ring is pushed home, therefore, the slots 25 will be in a position to receive the screws 19. Thereupon the ring is turned on the screws until the bell 2 is gripped by the rims 17 and 23 30 with sufficient firmness. The ring 14 is fitted with internal lugs 24 whereby its rotary displacement relative to the hood can be easily effected. As the rims exert a uniform and yielding pressure on the bell 2, 35 the latter will not be liable to crack during assemblage or during use, as when held direct by the fastening screws in the usual manner. The upper edges of the slots 25 may be serrated as shown in Fig. 5, the better to retain the ring 14 in adjusted position.

To allow an adjustment of the lamp 5 relative to the reflector 2^a, the lamp holder 30 is fitted in a bridge 29 which is slidably held 45 on the limbs of a U-shaped, vertical shackle 28 suspended from the top of the hood 1. The shackle is resilient and is constrained by the bridge 29 so that the latter will be retained by spring-action in any position of 50 the limbs to which it may be adjusted.

If a dim light should be required from two lamps connected in series, a yoke 31 (Fig. 7) is connected to the bridge 29 for holding the two lamps 36. The holders 35 55 for these lamps are connected to the right-angled lower ends of two slides 32 which are guided longitudinally in the vertical, channelled members of the yoke 31. The slides are secured to the yoke by means of screws 33 which pass through longitudinal slots 34 in the slides. By this arrangement 60 all the holders can be adjusted so that a

lamp inserted in either, will be in its proper position relative to the reflector 2^a.

When partly direct and partly indirect 65 lighting is required, the arrangement shown in Fig. 10 may be resorted to. In this case the globe is composed of two bell-shaped parts 37 and 38^a which are connected by means of a metal rim 4 in the same manner as described in connection with Fig. 1. The reflecting surface for the horizontally emitted light rays is in this case formed at 38^a in the lower globe part so that the light is reflected upwards either against the ceiling 75 or against another reflector 39 which may be connected to the hood 1. The central portion of the lower bell is translucent so as to admit diffused light direct. The bell 37 is transparent so as to admit all the direct or reflected light to the ceiling or to the reflector 39. The center portion of the lower bell can also be transparent if the lower part of the lamp bulb 5 is frosted. The advantage 80 of using the reflector 39 is that its inclination can be regulated for throwing the light in a definite direction. If the same kind of lamp is always used, the arrangement for adjusting the position of the lamp holder can be dispensed with.

The rim which connects the two globe parts may be utilized for exhibiting illuminated signs, as shown in Fig. 11. For this purpose, the rim may be composed of two parts 4 and 4^a which are distanced by means 95 of stays 40. The transparency 41 is arranged between the two parts of the rim behind the stays 40. It may either be made of glass or some opaque material which is suitably perforated.

The device may be subjected to further modifications within the scope of the invention. For instance the globe may be made in a single piece, and it may be supported on a pedestal instead of being suspended as 105 shown.

I claim:

A lamp shade of the character described, comprising a globe divided into an upper and a lower part, two hingedly connected metal mounts having resilient tongues and being connected to said globe parts, one to each, by the bending over of said tongues, a globe holder comprising a hood, a slotted ring nested within said hood, said hood and ring being provided with conical rims between which the globe can be clamped, and radial screws connected to the hood so that they can be engaged in the slots of said ring for holding the parts together, the slots being inclined so that the rims can be clamped to the globe by a relative rotary displacement of the holder parts.

JOSEF MERSING.
